UNITED STATES PATENT OFFICE

STEVE SCHNELL, OF ST. LOUIS, MISSOURI, ASSIGNOR TO WAGNER ELECTRIC CORPORATION, OF ST. LOUIS, MISSOURI, A CORPORATION OF DELAWARE

BRAKE MECHANISM

Application filed June 1, 1931. Serial No. 541,355.

My invention relates to braking apparatus and particularly to expanding brakes of the type employing auxiliary means spaced from the brake actuating device to produce a 5 radial pressure on the shoe to augment its pressure on the drum.

In internal expanding brakes comprising a "shoe" of the circular band type, which is applied to the brake drum by expanding 10 the adjacent free ends by some suitable means, the braking effect may be substantially increased by applying radial pressure to the band at a point intermediate its ends. This also results in more uniform wear of 15 the brake lining and consequently decrease in cost of maintenance.

One prior method of applying radial pressure to the brake band comprises the use of 20 cooperating inclined planes fixed to the band and to the backing plate at proper intervals about the circumference of the drum to radially force the intermediate part of the band into engagement with the drum upon 25 circumferential movement of the band with the drum when the brakes are applied. In this type of auxiliary means to produce a radial pressure on the shoe, the inclined surface on the shoe is in direct contact with the fixed inclined surface on the backing plate, 30 and there is present a high coefficient of friction, depending upon the type of surface used and, as the shoe is forced between the fixed inclined surface and the drum by the circumferential movement of the shoe with 35 the drum, there results a wedging effect. As the slope of the inclined surfaces is decreased,—that is, the angle between the inclined surfaces and a tangent drawn to the circumference of the drum where the projections of the inclined surfaces intersect 40 the drum, is increased, the wedging effect increases until a point is reached where the shoe will be locked to the drum (a very undesirable feature in brakes). The slope 45 of the inclined surfaces, therefore, determines the safe radial force that can be applied to the shoe by this type of pressure producing means. This safe radial force is not as large as is desired in this type of 50 brake and, therefore, it is an important

object of my invention to construct an auxiliary device of the inclined surface type that will produce a greater radial force against the shoe and at the same time eliminate the possibility of any tendency to lock 55 the drum.

Another object of my invention is to construct an independently acting means for applying radial pressure to a brake shoe to urge it against the drum which is cheap to 60 manufacture, efficient in operation, and requires little or no special attention in maintenance.

In the drawings Figure 1 is a front view of a brake disclosing apparatus embodying 65 my invention applied to the central part of an expanding shoe; Figure 2 is a cross sectional view on the line 2—2 of Figure 1; Figure 3 is a cross sectional view on the line 70 3—3 of Figure 1; Figure 4 is a front view 70 of a modification; and Figure 5 is a front view of still another modification (showing only the lower part of the brake).

Referring to Figures 1, 2, and 3 of the drawings, 1 indicates a brake drum, and 75 enclosing the open side of the drum is a backing plate 2 secured by suitable means to the axle housing or some fixed part of the vehicle. Mounted within the drum is a circular metal expansible brake band 3 carrying a suitable lining 4. A fluid cylinder 5 having the usual actuating pistons is mounted between the adjacent ends of the band for expanding it against the drum. A sufficiently strong spring 6 is also connected 80 to the ends of the band to retract the band from the drum when the pressure on the actuating pistons has been relieved.

Mounted by means of rivets on the backing plate 2 adjacent the central part of the band and spaced from the backing plate by spacers 7 is a fixed member 8. This fixed member has cut therein, on the edge adjacent the band, two oppositely inclined surfaces 9 and 10 diverging toward the drum 95 to form an inverted V-shaped recess. Riveted to the web 11 of the brake is a pair of plates 12 and 13, one on each side of the web, and each having opposed inclined surfaces 14 and 15 in the inwardly extending 100

edge which diverge toward the center of the drum to form a V-shaped recess. The fixed member 8 is so spaced from the backing plate that it lies between the two plates 12 and 13 fixed to the web of the band with the open end of its V-shaped recess overlapping the open end of the V-shaped recess in the plates 12 and 13. Mounted in the space formed by the sides of the V-shaped recesses is a floating roller 16 having enlarged ends 17 and 18. The enlarged ends of the roller are adapted to be in rolling contact with the V-shaped recesses of the plates 12 and 13 and the central part of the roller is adapted to be in rolling contact with the V-shaped recess in the plate 8, and since it projects between the enlarged ends of the roller, this plate maintains the roller in operative position by preventing its axial movement.

An eccentric stop member 19 (see Figure 3), comprising a bolt 20, spring 21, and head 20' is mounted on the backing plate 2 adjacent the roller for adjusting the "off" position of the brake band with respect to the drum. Springs 22 and 23 hold the band against the stop 19 when the brake is not applied, and spring 22 is preferably so positioned that its pull on the band has a circumferential component whereby, in "off" position of the brakes, the roller is held in contact with opposing walls of the recesses. Spaced approximately 120 degrees on each side of the eccentric stop 19 is a pair of similar stops 24 and 25 for determining the "off" position of the ends of the band. The three stops 19, 24 and 25, being spaced as shown, constitute a very convenient means for insuring equal clearance of the brake lining from the drum throughout its entire circumference when in its released position.

In the operation of the brake, when the ends of the band 3 are expanded into engagement with the drum 1 by means of the cylinder pistons, the band tends to travel with the drum and if the drum is rotating in the direction of the arrow (Figure 1) the band will also be carried in the same direction. This causes the inclined surface 15 of the left hand sides of the recesses in plates 12 and 13, to be forced against the roller 16 and the roller in turn to be forced against the fixed inclined surface 9 on the right hand side of the recess in plate 8 and thus the band is forced into frictional engagement with the drum against the tension of spring 23. The greater the circumferential "drag" on the band the greater the radial force exerted upon the band by the cooperating inclined surfaces and the roller means. The amount of radial force exerted on the band can be varied by changing the angle of the inclined surfaces 15 and 9 but regardless of the angle, within any desired

limits, there will be no tendency of the roller to lock the band against the drum by a wedging effect since the roller member 16 has a rolling contact with the inclined surfaces at all times. This results in the possibility of securing any desired ratio between radial pressure against the band and the circumferential torque. It is found in practice that a convenient angle for the inclined surfaces is approximately 30 degrees with respect to a drum radius passing through the roller.

The operation of the brake, when the drum is rotating in the opposite direction, is the same as above described except that the inclined surfaces 10 and 14 now cooperate with the roller to force the band against the drum.

In the modification shown in Figure 4, there is disclosed an auxiliary radial force producing device for the band when it is carried with the drum in one direction and a radially extending anchor surface for the band when it is carried with the drum in the other direction. The structure is very similar to that shown in Figure 1 with the exception that one side of the recesses in the plates 8, 12 and 13 is approximately parallel to a drum radius passing through the center of the roller 16, as clearly shown at 10' and 14'. When the drum is rotating in the direction of the arrow, the operation of the inclined surfaces is the same as described with respect to Figure 1, the inclined surfaces 9 and 15 acting through the roller 16 to force the band toward the drum. When the drum is rotating in the opposite direction (rearward motion of the vehicle) and the band is actuated to apply the brake, the surface 14' will move the roller 16 against the surface 10' on the fixed plate 8 as the band is carried with the drum and no radial force will be applied by these parts. By locating the anchor device somewhat to the right of the center of the band, as shown in Figure 4, the "wrapping effect" is increased in the manner well understood and it is a matter of choice, from the standpoint of braking effect desired, at what point intermediate the ends of the brake band any of the anchoring devices herein shown, are located.

A spring 26 is fixed to the band and the backing plate 2 to assist in releasing the band from the drum upon release of the actuator and to at all times keep the inclined surfaces in contact with the interposed floating roller whereby there will be no lost motion nor consequent noise resulting from engagement of the parts when the brake is applied. The stops 19, 24 and 25 are equally spaced about the circumference of the band in a similar manner as described with respect to Figure 1.

In the modification disclosed in Figure 5, anchoring devices like that of Figure 4 are

on each side of the central part of the brake band. In this figure the plate 27 is spaced from the backing plate in a similar manner as the plate of Figure 1 and has the inclined surface 10 formed in the edge thereof and a pair of plates 29 having inclined surfaces 14, parallel with the inclined surface 10, are fixed to the band web 11. The roller is placed between the inclined surfaces 10 and 14 and is in rolling contact therewith. The other anchoring device is similar, the inclined surface 9 of the fixed plate 28 being parallel with the inclined surfaces 15 on the plates 30 fixed to the band and the roller 16 in rolling contact with the inclined surfaces. Springs 22 and 23 retract the band from the drum when the actuator is released. It is to be noted that this modification does not have the radial surfaces 10' and 14' shown in Figure 4 and, therefore, the band has a tendency to be carried with the drum in both directions of rotation of the drum when the brake is applied. This allows the inclined surfaces 9 and 15 and the roller 16 to force the band against the drum in one direction of rotation and the inclined surfaces 10 and 14 to force the band against the drum in the other direction of rotation. The stops 19, 24 and 25 are preferably equally spaced about the band in the same manner as in Figure 4.

As indicated in Figures 1 and 2, I prefer to provide the shoe plates 12 and 13 with extensions 31 which project into slots formed in the shoe flange to receive the circumferential thrust of the shoe and thus avoid the necessity of applying sufficient rivets for this purpose.

Having fully described my invention, what I claim as new and desire to secure by Letters Patent of the United States is:

1. In braking apparatus, the combination of a rotatable drum, a friction member adapted to cooperate therewith, said member being capable of slight circumferential movement with the drum, and means for applying radial pressure to said member, said means comprising two abutment elements having inclined surfaces and an element in contact with both of said surfaces and adapted to roll thereon.

2. In braking apparatus, the combination of a brake drum, a brake shoe adapted to cooperate therewith, an anchorage for the shoe having a stationary inclined surface, means on the shoe forming a second inclined surface, and a member interposed between and in rolling contact with each of said surfaces, whereby radial pressure is applied to the shoe in response to circumferential movement of the shoe.

3. A brake comprising a friction device and an adjacent stationary support, anchor means for said friction device including an inclined surface on the friction device and

a member on the support having an inclined surface, and a floating roller interposed between and contacting with the two inclined surfaces.

4. In braking apparatus, the combination of a support, a brake drum, a friction member carried by the support and adapted to cooperate with the drum, means to actuate said friction member into engagement with the drum, said friction member being adapted to have a slight rotative movement with the drum, said friction member being provided with an inclined surface spaced from the actuating means, an anchor member carried by the support and provided with a surface inclined in the same direction as said inclined surface on the friction member, and a floating roller interposed between said surfaces.

5. In braking apparatus, the combination of a support, a rotatable member, a friction element for cooperation therewith, means to actuate the friction element, anchor means for limiting the movement of the friction element with the rotatable member and for forcing said element into engagement with the rotatable member, said anchor means comprising a member having an inclined surface and secured to the friction element, a second member having an inclined surface parallel with the first named inclined surface and secured to the support, a floating member interposed between and in rolling contact with the surfaces, and means for holding the floating member in contact with the inclined surfaces when the friction element is in off position.

6. In braking apparatus, the combination of a rotatable member, a shoe for frictional engagement therewith and provided with an inclined surface, a fixed member having a surface inclined in the same direction as the first named surface but spaced therefrom, a floating roller member in rolling contact with said inclined surfaces, and means for preventing axial movement of the roller member.

7. In braking apparatus, the combination of a rotatable member, a friction element cooperating therewith and having a pair of surfaces diverging away from the adjacent portion of the rotatable member, an anchorage for said friction element comprising a fixed member having a pair of abutment surfaces diverging toward the said rotatable member and radially aligned with the first mentioned pair of diverging surfaces, and a floating element cooperating with both pairs of surfaces to limit movement of the friction element with the drum.

8. In braking apparatus, the combination of a rotatable drum, a friction member adapted to cooperate with the drum and having a slight circumferential movement with the drum when in engagement there-

with, said member being provided with a V-shaped recess, anchor means for the friction element intermediate its ends and comprising a fixed abutment member provided with a V-shaped recess adjacent the first named recess, and a floating roller cooperating with the sides of both recesses.

9. In braking apparatus, the combination of a fixed support, a rotatable member, a friction element adapted to cooperate with said member, means on said friction element forming an abutment surface, an anchor member secured to said support and having an abutment surface thereon adjacent the first named surface, a roller interposed between said surfaces, and means for holding the roller in contact with said surfaces when the friction element is in "off" position.

10. In braking apparatus, the combination of a rotatable member, a friction element adapted to cooperate with said member, and means for applying radial pressure to the friction element intermediate the ends thereof, said means comprising elements having inclined surfaces and a roller in rolling contact with said inclined surfaces, said roller having enlarged ends cooperating with one of said elements to retain the roller in position.

11. In braking apparatus, the combination of a support, a rotatable member, an expansible friction element adapted to cooperate therewith, means, including a roller, intermediate the ends of said expansible friction element for applying radial pressure to said element when the rotatable member is rotating in one direction, and means cooperating with the roller for preventing circumferential movement of the friction element with the rotatable member when the member is rotating in the opposite direction.

12. In braking apparatus, the combination of a rotatable drum, an expansible brake shoe adapted to cooperate with the drum, an abutment member having inclined surfaces diverging toward the drum periphery, a pair of members fixed to the shoe and having inclined surfaces diverging toward the center of the drum, and a floating roller, said roller having enlarged ends cooperating with the inclined surfaces of the members fixed to the shoe and the central part cooperating with the inclined surfaces on the abutment member.

13. In braking apparatus, the combination of a support, a rotatable drum, an expansible brake band adapted to cooperate with the drum, said band having slight circumferential movement with the drum when in engagement therewith, a pair of spaced apart auxiliary applying devices for radially forcing the band into engagement with the drum, one being operative in one direction of rotation of the drum and the other being operative in the other direction of

rotation of the drum, each device comprising a member fixed to the support and having an inclined surface thereon and a second member fixed to the band and having an inclined surface spaced from the inclined surface on the fixed member, each auxiliary applying device also comprising a floating roller interposed between and in rolling contact with the said inclined surfaces.

14. An auxiliary applying device for an expansible brake shoe comprising a pair of parallel members fixed to the shoe and each provided with an inclined surface, a fixed member interposed between the members fixed to the shoe and provided with an inclined surface adjacent the first named inclined surfaces, and a floating element in rolling contact with all of said inclined surfaces.

15. In braking apparatus, the combination of a rotatable element, an expansible brake shoe adapted to cooperate with said element, a pair of members fixed to the brake shoe and each provided with a V-shaped recess therein, a fixed member having a V-shaped recess therein and interposed between the pair of members fixed to the shoe and a floating roller, said roller having enlarged ends cooperating with the sides of the V-shaped recesses of the members fixed to the brake shoe, and the central part cooperating with the sides of the V-shaped recess of the fixed member.

16. An auxiliary applying device for an expansible brake shoe, comprising a pair of parallel members carried by the shoe and each having inclined surfaces, a fixed member interposed between the members fixed to the shoe and provided with inclined surfaces, and a floating roller, the ends of the roller having a greater circumference than the central part, said ends cooperating with the inclined surfaces on the members fixed to the shoe and the central part cooperating with the inclined surfaces on the fixed member, said fixed member also cooperating with the ends of the roller to prevent axial movement of the roller, and spring means for maintaining contact between the walls and the inclined surfaces when the brake shoe is in "off" position.

17. In braking apparatus, the combination of a support, a rotatable drum, a brake shoe adapted to cooperate therewith, said shoe having slight rotative movement with the drum when in engagement therewith, a member fixed to the support and provided with a recess therein, one side of said recess being substantially parallel to a drum radius and the other side of the recess being inclined thereto, a member fixed to the shoe and having a recess therein similar to the first mentioned recess with its inclined side inclined in the same direction as the inclined side of the fixed member and spaced there-

from, and a floating member in rolling contact with the sides of the recesses.

18. In braking apparatus, the combination of a support, a brake drum, a friction member carried by the support and adapted to cooperate with the drum, the friction member being adapted to have a slight rotative movement with the drum when applied thereto, said friction member being provided with an inclined surface, an anchor member carried by the support and provided with an inclined surface parallel with the inclined surface of the friction member, and a floating roller interposed between said surfaces and in rolling contact therewith whereby when the friction member is applied to the drum the rotative movement of the friction member with the drum will cause the inclined surface on the friction member to move relatively to and parallel with the inclined surface on the anchor member and force the friction member into tighter engagement with the drum.

19. In braking apparatus, the combination of a support, a brake drum, a brake band carried by the support and adapted to engage the major portion of the circumference of the drum, means between the ends of the band for expanding the band into engagement with the drum, the band being adapted to have a slight rotative movement with the drum when applied thereto, said band being provided with an inclined surface intermediate its ends, an anchor member on the support and provided with an inclined surface adjacent the first named inclined surface, and a floating roller interposed between said surfaces and in rolling contact therewith.

40 In testimony whereof, I hereunto affix my signature, this 22nd day of May, 1931.

STEVE SCHNELL.
